DRAFTING INSTRUMENT

Samuel S. Cary, Jennings, La.

Application September 8, 1934, Serial No. 743,283

4 Claims. (Cl. 33—20)

This invention relates to the class of drafting instruments and pertains particularly to a device for facilitating the drawing of contours.

The primary object of the present invention is to provide a device which is designed to be used upon a plane table and which may be used in conjunction with a compass and range finder, whereby an object or horizon contour may be sighted and transferred through mechanism operating in coordination with the sighting mechanism to a drawing paper disposed upon the plane table.

Another object of the invention is to provide a drawing instrument wherein a horizontally movable marker or scribe is coupled with a vertically and horizontally movable sighting element whereby the movement of the sighting element either vertically or horizontally will be transferred through the scribing element to a drawing paper located therebeneath.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view in top plan of the instrument embodying the present invention.

Figure 2 is a sectional view taken on the line 2—2 of Figure 1.

Figure 3 is a sectional view taken on the line 3—3 of Figure 1.

Figure 4 is a view in elevation of a stationary sight forming a part of the instrument.

Referring to the drawing, the numeral 1 indicates a working surface of any suitable character such, for example, as a plane table, which is normally supported upon a tripod, the legs of which are indicated by the numerals 2, upon which table or work surface, the mechanism embodying the present invention is shown mounted.

The present invention comprises a guide of any suitable character which is here indicated by the numeral 3 and illustrated as comprising a pair of plates 4 and 5 fixed in spaced parallel relation to the table to extend across one edge of the same, which edge constitutes the back of the table when the present instrument is in use.

These elongated plates or guide elements 4 and

5 are each provided with an inwardly directed flange 6 and between the plates is slidably disposed a two-part block 7, which is provided with grooves 8 upon opposite faces to slidably receive the flanges 6, as illustrated in Figure 3. The block 7 has a chamber 9 therein in which is rotatably disposed a relatively broad gear wheel 10, and passages 11 and 12 extend, respectively, vertically and horizontally through the block 7 and have communication with the gear chamber 9, as illustrated in Figure 3. The table has a slot 13 therein, which extends parallel with the back edge and lies beneath the slot 11, and the plates 4 and 5 are also provided with longitudinally extending slots which are indicated by the numeral 14, which are in the same plane as the passage 12 in the block 7.

Extending longitudinally of and between the plates 4 and 5 is a shaft 15 of polygonal cross section which passes through the gear 12 and is rotatably supported at its ends in the bearings 16. The gear 10 is slideable on this shaft but cannot rotate independently thereof. At one end, the shaft 15 has a beveled gear 17 thereon which meshes with a similar gear 18 mounted upon the shaft 19 which extends from the rear edge of the table to the forward edge thereof, where it is supported by the bearing 20 and carries a hand wheel 21. The end of the shaft 19 which carries the gear 18 passes through and is supported by the inner plate 5. Disposed at the opposite side of the table from the shaft 19 is a shaft 22 which is supported, as indicated at 23, adjacent the front edge of the table and carries upon the end adjacent this edge the hand wheel 24. The rear end of the shaft 22 passes through and is supported by the plates 4 and 5 and carries a sprocket wheel 25. At the opposite end of the plate 4 from the end adjacent the sprocket wheel 25, is mounted a similar sprocket wheel 26, and these wheels have a sprocket chain 27 passing thereover and connected with the block 7, as indicated at 28. It will thus be apparent that by rotating the hand wheel 24, the sprocket chain will be caused to move over the wheels 25 and 26 and shift the gear carrying block 7.

Extending horizontally over the surface of the table 1 and passing through the passage 12 of the block and the passages 14 of the plates 4 and 5, is a rack bar 28 which has its teeth in engagement with the teeth of the gear 10. This bar constitutes a marker carrying arm having at its inner end a suitable socket or other means 30 for receiving and holding a pencil or other suitable marker 31 which extends downwardly toward the 55

- top surface of the table. Extending vertically through the slot 13 of the table and through the passage 11 of the block 7 is a second rack bar which is indicated by the numeral 32, and which 5 also has its teeth in engagement with the teeth of the wheel 10. This bar 32 constitutes a movable sight bar, the upper end being formed to provide a sight 33, which is here illustrated as being in the form of a ring or eye.
- 10 At the front edge of the table 1 and preferably at the center of this edge is mounted a fixed sight bar or standard 34, the upper end of which carries an eye or other suitable sight 35 for use in association with the sight 33 of the movable 15 sight bar.

From the foregoing, it is believed to be apparent that in the operation of the present instrument, after a drawing paper has been secured to the table 1, the table is positioned between the user 20 and the object which is to be outlined upon the paper with the movable sight bar 32 between the object and the fixed bar 34. By then lining up the sights 33—35 with the edge of the object to be outlined on the paper and manipulating the 25 hand wheels 21 and 24, the sight 33 can be caused to follow the outline of the object, and it will be apparent that every movement of this sight will be transferred to the scribing bar or arm 29, and the marker 31 will be caused to move over the 30 surface of the drawing paper and thus outline the object thereon.

What is claimed is:—

1. An instrument, comprising a drawing surface, guide means extending along one side of said surface, a body mounted upon said guide means for movement along said side, an arm carried by said body and movable in a plane paralleling said surface and at right angles to the direction of movement of the body, a vertical member carried 35 by said body and movable vertically therethrough, means carried by the body coupling said vertical member and said arm whereby vertical movement of the said member will be effected simultaneously with reciprocatory movement of said 40 arm, a sight carried by the vertical member, a marker carried by and fixed to the arm, a fixed sight disposed at the opposite side of the surface from the sight upon said member, means for effecting movement of said body, and means for 45 effecting simultaneous movement of the arm and member.
2. An instrument of the character described, comprising a work surface, means forming a pair of guides in parallel relation at one side of said 50 surface, a body slidably mounted on and between said guides, a gear rotatably carried by the body, a shaft paralleling the guides and having sliding

connection with said gear, means for rotating the shaft from a point at the opposite side of the work surface from the guides, a rack member passing through the body and disposed vertically and having toothed connection with the gear, a 5 rack member passing through the body and paralleling the work surface and having toothed connection with the gear, a sight carried by said vertical rack member, a marker carried by the horizontal rack member, a fixed sight disposed at the 10 opposite side of the work surface from the vertical rack, and means operable from the opposite side of the work surface from the body for effecting the movement of the body in either direction on said guides.

3. An instrument of the character described, comprising a board constituting a work surface, a body mounted on said board, supporting means for said body facilitating its movement in a path adjacent an edge of the board, a pair of elongated members extending at right angles through said body, one of said members being disposed at right angles to the surface of the board and the other of said members being disposed parallel to the board surface to extend across the same, 25 means carried by said vertical member at its upper end providing a sight, a marker fixed to the member paralleling the board at the end overlying the board, means carried by said body and coupling said members whereby the members 30 may be moved longitudinally in unison, means facilitating the manipulation of the member coupling means from a point remote from the body, means facilitating the movement of the body and the elongated members carried thereby on said 35 supporting means, from a point remote from the body, and a fixed sight carried by the board for co-action with the first sight.

4. An instrument of the character described, comprising a drawing surface, a body disposed at 40 one side of the drawing surface, means supporting said body facilitating its movement along the said side of the drawing surface, means for effecting the movement of the body, a pair of arm members disposed in right angular relation one 45 thereof overlying and extending parallel with the drawing surface, said arms passing through said body, a marker carried by the said one of the arms, a sight carried by the other one of said arms, an element carried by said body and having movement relative thereto and coupling said arms whereby movement of the element will effect the simultaneous longitudinal movement of the arms, means for effecting the movement of the element, and a second sight fixed relative to the arm carried 55 sight.

SAMUEL S. CARY.
